UNITED STATES PATENT OFFICE.

LOUIS L. LASOTA, OF LACKAWANNA, NEW YORK.

CAR-COUPING.

1,360,233.

Specification of Letters Patent. Patented Nov. 23, 1920.

Application filed June 23, 1920. Serial No. 391,098.

To all whom it may concern:

Be it known that I, LOUIS L. LASOTA, a citizen of Poland, residing at Lackawanna, in the county of Erie and State of New York, have invented certain new and useful Improvements in Car-Couplings, of which the following is a specification.

This invention relates to certain new and useful improvements in car couplers and has for its primary object to provide a car coupler wherein each coupling block carries a slotted link and an engaging hook to constitute a double connection between the coupling blocks.

A further object of the invention resides in the provision of coupling mechanism for cars wherein there is provided a coupling link carried by each block for engagement with a keeper hook carried by the opposite block with an operating lever on each block adapted for simultaneous releasing movement of the two connecting link members.

With the above general objects in view and others that will appear as the nature of the invention is better understood, the same consists in the novel form, combination and arrangement of parts hereinafter more fully described, shown in the accompanying drawings and claimed.

In the drawings, wherein like reference characters indicate corresponding parts throughout the several views,

Figure 1 is a side elevational view of two connected coupling blocks,

Fig. 2 is a longitudinal sectional view of the same with the coupling links lowered into engaging position with the keeper hooks,

Fig. 3 is a longitudinal sectional view similar to Fig. 2 showing one of the arms for releasing the coupling link in its elevated position with the coupling link disengaged from the keeper hook,

Fig. 4 is a horizontal sectional view taken on line IV—IV of Fig. 1 showing the two compartments in one coupling block for containing a coupling link and keeper hook,

Fig. 5 is an end elevational view of one of the coupling blocks,

Fig. 6 is a vertical sectional view taken on line VI—VI of Fig. 2 showing the operating arm for the adjacent coupling link in its lowered position, and

Fig. 7 is a perspective view of the operating arm for the coupling link detached from the coupling block.

The coupling blocks disclosed in the ac-

companying drawings being of identical construction, only one of said blocks will be described in detail, each coupling block comprising a connecting bar 1 having an enlarged rectangular head 2 at the outer end thereof. The block 2 is provided with a pair of end entrance compartments 3 and 4 for housing the coupling link 5 and keeper hook 6 respectively, said compartments 3 and 4 being separated by a central partition 7.

The compartment 3 is provided with an inclined upper wall 8 terminating at the outer end of the block 2 while the lower end of the entrance opening to the compartment 7 is provided with an abutment wall 9.

The coupling link 5 of the type best illustrated in Figs. 2, 3 and 4 is pivotally mounted at its inner end upon the transverse bolt 10 extending through the compartment 4 and the rear slot 11 communicating with the compartment 3, the connected link 5 being pivotally mounted for vertically swinging movement. The forward end of the coupling link 5 is provided with a longitudinal slot 12 closed at the outer end by the wall 13 having an inner beveled surface 14 and an outer beveled surface 15.

The keeper hook 6 is positioned within the compartment 4 and through which the bolt 10 passes, as indicated in Figs. 2, 3, and 4, and the coupling links and hooks of co-operating blocks are positioned to present the outer projecting slotted end of the coupling link for reception in the opposite compartment 4 for engagement with the keeper hook 6. The blocks in being moved toward each other will cause the outer beveled ends 15 of the coupling link ends 13 to ride over the beveled edge 16 of the forward lower abutment wall of the compartment 4, thereby slightly to elevate the free ends of the coupling links to position for sliding engagement with the keeper hooks 6 and causing positioning of the slotted portion of the coupling links over the keeper hooks for reception thereof to retain the coupling blocks connected.

In order to effect a release of the coupling links from the keeper hooks and to disconnect the coupling blocks 2, a vertically shiftable operating arm is carried by each block, the arm being shown in detail in Fig. 7 as embodying a vertical shank 17 carrying an angular extension 18 adjacent its lower end 110 with a cross head 19 at the free end of the extension and provided upon the upper end

thereof with operating faces 20 and 21. The bottom wall of the compartment 3 is provided with a T-shaped slot, the leg 22 of each slot extending longitudinally of the 5 wall while the cross head 23 thereof extends to the compartment 4 and is alined with a vertical slot 24 in the partition 7. A vertical slot 25 is provided in the upper wall of the block and is in vertical alinement with 10 the rear end of the slot 22. The operating arm is introduced into the block through the lower slotted end thereof, the shank 17 entering the slot 22 and passing into the opening 25 for projection above the block 15 2 and retained in position by the link 26. The shank extension 18 passes through the slot 22 while the cross head 19 enters the head portion 23 of the slot. The operating face 21 extends into the compartment 3 20 while the operating face 20 extends into the compartment 4 and both operating faces underlie the coupling links 5.

When it is desired to uncouple the blocks 2, either of the operating arms 17 is elevated 25 vertically to shift the head 19 to elevate the coupling link 5 to the position shown in Fig. 3. The operating face of the head 19 engages the link 21 carried by the same block while the operating face 20 engages the end 30 of the link 5 carried by the opposite block. Either of the operating arms 17 may be employed for releasing the coupling links 5 from the keeper hooks 6 and operating means of any preferred type may be attached to the arm links 26. As shown in 35 Figs. 2 and 6, the lower end of the head 19 is tapered and projects downwardly through the head portion 23 of the T slot and may be struck with a suitable implement to start 40 the elevating movement of the operating arm.

While there is herein shown and described the preferred embodiment of the present invention, it is nevertheless to be understood 45 that minor changes may be made therein without departing from the spirit and scope of the invention as claimed.

What is claimed as new is:—

1. A car coupler of the type described 50 comprising companion coupling members each embodying a head, there being compartments in said head and a partition separating the compartments, a bolt extending transversely of said compartments, a coupling link within one of said compartments and supported on said bolt, and a keeper hook in the other compartment pivoted upon said bolt, the coupling link of one block engaging the keeper of the opposed block.
60. 2. A car coupler of the type described comprising companion coupling members each embodying a head, there being com-

partments in said head and a partition separating the compartments, a bolt extending transversely of said compartments, a coupling link within one of said compartments and supported on said bolt, a keeper hook in the other compartment pivoted upon said bolt, the coupling link of one block engaging the keeper of the opposed block, and 70 means for releasing the coupling links from the hooks.

3. A car coupler of the type described comprising companion coupling members each embodying a head, there being compartments in said head and a partition separating the compartments, a bolt extending transversely of said compartments, a coupling link within one of said compartments and supported on said bolt, a keeper hook 75 in the other compartment pivoted upon said bolt, the coupling link of one block engaging the keeper of the opposed block, and means for simultaneously shifting the coupling link of each head to a disengaging position relative to the keeper hooks.

4. A car coupler of the type described comprising companion coupling members each embodying a head, there being compartments in said head and a partition separating the compartments, a bolt extending transversely of said compartments, a coupling link within one of said compartments and supported on said bolt, a keeper hook 90 in the other compartment pivoted upon said bolt, the coupling link of one block engaging the keeper of the opposed block, an arm vertically slidable in each block, and a T-shaped head carried by the lower end of said arm and underlying the coupling links 95 to elevate the same to disengaging positions relative to the keeper hooks.

5. A car coupler of the type described comprising companion coupling members each embodying a head, there being compartments in said head and a partition separating the compartments, a bolt extending transversely of said compartments, a coupling link within one of said compartments and supported on said bolt, a keeper hook 105 in the other compartment pivoted upon said bolt, the coupling link of one block engaging the keeper of the opposed block, an arm vertically slidable in each block, and a T-shaped head carried by the lower end of 110 said arm and underlying the coupling links to elevate the same to disengaging positions relative to the keeper hooks, the partition between the compartments and the bottom wall of the block being slotted to permit 115 the vertical sliding movement of the operating arm.

In testimony whereof I affix my signature.
LOUIS L. LASOTA.
